US0D1102126S

(12) United States Design Patent (10) Patent No.: US D1,102,126 S
(45) Date of Patent:  Nov. 18, 2025

(54) SHOE

(71) Applicant: NIKE, Inc., Beaverton, OR (US)

(72) Inventor: Cristian Gonzalez, Portland, OR (US)

(73) Assignee: NIKE, Inc., Beaverton, OR (US)

() Term: 15 Years

(21) Appl. No.: 29/951,957

(22) Filed: Jul. 12, 2024

(51) LOC (15) Cl. 02-04

(52) U.S. Cl.

USPC D2/972

Primary Examiner — Jonathan J Han

(74) Attorney, Agent, or Firm — Banner & Witcoff, Ltd.

(57) CLAIM

The ornamental design for a shoe as shown and described.

DESCRIPTION

FIG. 1 is a side view of a shoe showing my new design; FIG. 2 is a front perspective view thereof;

FIG. 3 is a front view thereof;

FIG. 4 is an opposite side front perspective view thereof; and,

FIG. 5 is an opposite side view thereof.

The parallel broken lines and the unshaded areas therebetween form no part of the claimed design. The broken line showing of the unshaded area on the toe box forms no part of the claimed design. The unshaded areas within the rectangular-shaped eyelets form no part of the claimed design. The broken lines depicting the remainder of the shoe form no part of the claimed design.

1 Claim, 5 Drawing Sheets
